DRIER CONTROL SYSTEM

Raymond E. Olson, Pittsford, N. Y., assignor to
Taylor Instrument Companies, Rochester, N. Y.,
a corporation of New York

Application September 10, 1942, Serial No. 457,887

3 Claims. (Cl. 34—41)

This invention relates to driers and particularly to driers of the type comprising one or more drums, internally heated by steam or other similar heating fluid. The drums of such driers are preferably pneumatically flushed of steam condensate and are also provided with vacuum relief means whereby atmospheric pressure is established within the drums to prevent them from collapsing as would otherwise occur when the drums cooled off at the time of shut-down. With the drums thus filled with air, it has been difficult in the starting of prior driers, to bring them up to predetermined temperature quickly since the air trapped in the drums tended to oppose the introduction of steam therein.

In accordance with the present invention, means are provided for automatically venting the air from the drums until such time as they reach a predetermined temperature after which the automatic venting means ceases to operate until the drums are again below the mentioned temperature.

Another feature of the invention relates to a drier having steam heated drums from which steam condensate is pneumatically flushed and means for venting the air from said drums under the control of the temperature of said condensate.

Various other features of the invention will appear from the detailed description and claims when taken with the drawing in which:

Fig. 1 is a diagrammatic showing of a drum type drier incorporating the present invention; and

Fig. 2 is a diagrammatic showing of the automatic vacuum relief valve and of the piping arrangement for introducing steam into each drum, as well as for pneumatically removing steam condensate therefrom.

The present invention is applied to a drier comprising a plurality of driven drums 5a, 5b and 5c provided with suitable trunnions 6 on which they are rotatable in parallel relation so that a strip S to be dried, passes in a zigzag path thereabout (Fig. 1). While three drums only are illustrated, it will be understood that the invention is not limited to any given number thereof but is applicable to one drum or any number of drums, as occasion demands.

The drums are preferably internally heated by steam supplied through a header 7 having branches 7a respectively communicating through a trunnion 6 of each of the several drums in order not to interfere with the rotation thereof. The flow of steam through the header is con-

trolled by a diaphragm motor valve 8 connected thereto, which valve is adapted to be closed by a pressure fluid, such as compressed air applied to its diaphragm motor. The application of compressed air to this diaphragm motor is governed by a suitable temperature controller C including a thermosensitive bulb B, similar to that shown in Fig. 1 of Foote Patent No. 2,088,055, granted July 27, 1937. The controller C, as herein utilized, operates in response to temperature changes in the steam condensate, sensed by the bulb B, to govern the application of compressed air from the supply pipe 22 through conduit 9 to the motor of valve 8 and to branch conduit 9a, which terminates in the relay valve 10.

It will be understood that in the course of the operation of the drier, steam will condense in each drum and this condensate must be removed therefrom.

For this purpose each drum is provided with a siphon exhaust pipe 11, terminating at one end adjacent a low point of each drum to dip into the condensate accumulating therein.

Each exhaust pipe likewise passes through one of the trunnions of its drum to communicate

25 through its individual trap 12 with a common condensate pipe 13. In order to sense the temperature of the condensate, the bulb B is mounted in one of the exhaust pipes 11 externally of its related drum. The interior of each drum during operation, is also supplied with compressed air or like pressure medium by means of the supply pipe 14 and its branches 14a which respectively pass through a trunnion of each of the several drums. This compressed air serves to flush the

30 condensate from the drums into the exhaust pipes 11 and thence into condensate pipe 13 thru the steam traps 12. It will be noted that each branch air pipe 14a has a check valve 15 therein to prevent steam from passing into the main air supply

pipe 14. Each exhaust pipe 11 also communicates through a check valve 17 with a common air vent pipe 18 which opens directly into the condensate discharge pipe 13. The check valves

40 17 prevent the interflow of the pressure mediums through the vent pipe 18 between the several drums. The flow through air vent pipe 18 is governed by a diaphragm motor valve 19 which is closed by the application of compressed air to

45 its motor. The application of compressed air to this motor is governed by the relay valve 10 which is opened by the application of compressed air thereto through the conduit 9a. It will be noted that conduit 9a communicates with con-

50 duit 9 so that relay valve 10 is opened when the

55 motor valve 19 is closed by the application of compressed air thereto through the conduit 9a. It will be noted that conduit 9a communicates with con-

duit 9 so that relay valve 10 is opened when the

diaphragm motor valve 8 is closed or is throttling the flow of steam through the header 1.

In this arrangement whenever the steam supply is turned off such as when the drier is shut down, the drums cool so that the contained steam and air contract developing subatmospheric pressures therein. In order to restore the interior of the drums to atmospheric pressure and thereby prevent the collapse thereof, an automatic vacuum release valve 20 is provided in each drum to open to the atmosphere in response to subatmospheric pressure therein.

Let it be assumed that it is desired to start the drier when the drums 5a, 5b and 5c thereof are cold and when they contain air at atmospheric pressure. At this time the motor valve 8 in the steam header 1 will be open and the motor valve 19 in the air vent pipe 18 will likewise be open. It is further assumed that a supply of steam under pressure is available at the header 1 and that a supply of compressed air is available in the air supply pipe 14. Under these conditions, steam will be introduced through the header 1 and its branches 1a into the respective drums and the air present within the drums is forced out through the air vent pipe 18. Since the drums are cold and since they will continue to give off heat during the drying operation, the steam will condense in the drums from which the condensate is flushed through the respective siphon exhaust pipes 11 by compressed air applied through branch pipes 14a. When the temperature of the condensate at the bulb B of the controller C reaches a predetermined temperature, the controller C will operate to apply compressed air through the supply pipe 22 to the diaphragm motor of the valve 8 and also to the operating chamber of the relay valve 10. Motor valve 8 in response to this pressure in its motor, as applied by controller C, will throttle the steam applied to the several drums to maintain them at a predetermined temperature. Also, when compressed air is applied to the chamber of the relay valve 10, this relay valve will open to permit compressed air from the supply pipe 22 to be applied to the diaphragm motor of the valve 19 in the air vent pipe. Valve 19 thus operates to close the air vent pipe. Thereafter, the operation of the drier is in accordance with the usual procedure wherein the condensate is discharged through the siphon exhaust pipes 11

and the several individual traps 12 to the common condensate pipe 13.

What I claim is:

1. The method of starting the operation of a drier, comprising a plurality of hollow drums which are arranged to be heated by a heating fluid introduced therein and which are provided with vacuum release mechanism whereby the space within said drums fills with air when the drier is shut down, which method comprises introducing steam into said drums while venting air therefrom, removing the condensate from said drums, sensing the temperature of the condensate in one of said drums, terminating the venting of said drums responsive to the attainment of a predetermined temperature of said condensate, and throttling the heating fluid introduced into said drums in response to the variation of a given value of the sensed temperature of said condensate to maintain said drums at a desired temperature which is greater than said predetermined temperature.

2. In a drier having a hollow drum, a pipe for supplying a heating medium to the interior of said drum, a valve connected in said pipe for governing the flow of the heating medium therethrough, means for relieving subatmospheric conditions within said drum, a conduit having a normally open valve connected therein to vent said drum, means for discharging condensate from said drum, and a controller operative substantially in accordance with a predetermined temperature within said drum for throttling said first mentioned valve and for closing said last-mentioned valve throughout the throttling operation.

3. In a drier having a hollow drum, a pipe for supplying steam to the interior of said drum, a diaphragm motor valve connected in said pipe for governing the flow of steam therethrough, means for relieving subatmospheric conditions within said drum, means for flushing condensate from said drum, a conduit having a normally open valve connected therein to vent said drum, means for discharging condensate from said drum and a controller responsive to a predetermined temperature of said condensate for throttling said first-mentioned valve and for closing said last-mentioned valve.

RAYMOND E. OLSON.
